UNITED STATES PATENT OFFICE

JAMES HALL TAYLOR, OF OAK PARK, ILLINOIS.

PROCESS OF MAKING PIPE-BENDS.

1,023,227.

Specification of Letters Patent. Patented Apr. 16, 1912.

Application filed October 3, 1910. Serial No. 585,008.

To all whom it may concern:

Be it known that I, JAMES HALL TAYLOR, a citizen of the United States, residing at Oak Park, in the county of Cook and State 5 of Illinois, have invented a certain new and useful Improvement in Processes of Making Pipe-Bends, of which the following is a full, clear, concise, and exact description, reference being had to the accompanying 10 drawings, forming a part of this specification.

My invention relates to wrought metal pipe manufacture and is particularly concerned with the making of bends in pipe of 15 this kind.

My invention is a process and, as will more fully appear hereinafter, is most useful in making slight or gradual turns or bends in wrought metal pipe of comparatively 20 large diameter.

Broadly, the process of my invention comprises two steps; first, stretching a portion 25 of the pipe wall out of the line of the contour of the pipe, and, second, straightening the portion thus stretched back into the substantial 30 contour of the pipe, a slight bend in the pipe resulting. Of course, the stretched portion of the pipe wall is diminished in thickness by the process, but the decrease is so small as to be negligible.

The above outlined process can be carried out in various ways, but, more specifically, the process which I contemplate as the most useful consists in first expanding a portion 35 of the pipe wall into an eccentric and consequently tapered bead, the metal within the defined area being therefore stretched so as to diminish in cross-sectional area. In straightening this expanded portion or bead, as will be apparent, a slight bend in the pipe 40 results, this process being repeated as often as necessary until the desired turn or bend is secured.

My invention will be more readily understood by reference to the accompanying drawings, in which—

Figure 1 is an elevational view of a straight section of pipe; Fig. 2 is an end view thereof; Fig. 3 is an elevational view of the section of pipe, showing the result of 50 the first step in the process; Fig. 4 is an end view of the pipe as shown in Fig. 3; Fig. 5 illustrates the result of the next step

in the process; Figs. 6 and 7 illustrate the manner of repeating the process; and Fig. 8 is an elevational view showing the finished product.

Let it be assumed, for the purposes of illustration, that it is desired to produce a bend of about five degrees in the pipe section *a*, 60 shown in Figs. 1 and 2. By means of suitable blocking on the outside of the pipe section and suitable blocking and expanding mechanism on the inside of the pipe section, the eccentric bead *b* is expanded 65 into the form shown in Figs. 3 and 4. The part of the pipe wall which is expanded is clearly and definitely defined by means of the blocking and an inspection of the drawings will show that the portion of the pipe 70 which is stretched in this way tapers in both directions toward that point in the pipe which will be on the inside of the resulting angle or bend. The axis of the pipe is maintained during this process of expanding the 75 bead and it follows that the cross-sectional area of the expanded portion of the wall of the pipe will be smallest at the point where the wall is expanded the most and will widen in both directions toward the coincident 80 ends at the point before referred to as that which will be on the inside of the bend. This much of the process being completed, the expanded portion is then brought back 85 into the substantial contour of the pipe, as shown in Fig. 5. The dot-and-dash lines *c*, *c* bound the stretched portion of the pipe, and, since the angle between these lines will be greater than the angle between the side lines of the tapered bead, the axis of the 90 portion *a*² of the pipe will no longer be coincident with the main axis. The cross-sectional thickness of the pipe between the lines *c*, *c* of course becomes less than it was originally, but the decrease by the process is so 95 slight as to be negligible. If the resultant bend, which has been described, is not sufficient, a second bead *b*² may be expanded directly adjacent the expanded and stretched portion *b* which formerly formed the bead, 100 as shown in Fig. 6, or further along in the pipe, if desired. In straightening the next bead back into the substantial contour of the pipe, a further and accumulating bend 105 is secured.

The center lines of the beads are pref-

erably at right angles, or substantially so, to the main center line of the pipe, and it is clear that they could be repeated indefinitely.

5 Fig. 7 shows how the process can be repeated until the desired bend, as shown in Fig. 8, is secured.

If a sharper turn is desired, the succeeding beads can be made to overlap, thus 10 stretching a portion of the pipe wall already stretched.

It is clear that the stretched portion of the pipe wall could extend inwardly of the pipe as well as outwardly therefrom and that a 15 number of stretched portions could be made and then simultaneously straightened.

In making an ordinary single bend the vertices of the tapered beads lie in a line substantially parallel to the main axis of 20 the pipe, but it will be evident that compound bends, that is a system of bends in different directions, can be secured by shifting these vertices either one way or the other.

I claim as new and desire to secure by Letters Patent:

1. The process of making bends in wrought metal pipe, which consists in expanding a portion of said pipe into a transverse bead tapered at both ends, and then straightening the metal thus stretched back 30 into the substantial contour of the pipe.

2. The process of making bends in wrought metal pipe, which consists in expanding a portion of the pipe bound by lines converging at both ends at a common point, 35 and then straightening the metal thus stretched back into the substantial contour of the pipe.

In witness whereof, I hereunto subscribe my name this 30th day of September, A. D. 40 1910.

JAMES HALL TAYLOR.
